DESIGN FOR A SHOE

Nicholas J. Grossman, Lynn, Mass., assignor to Philco Shoe Corporation, Salem, Mass., a corporation of Massachusetts

Application July 12, 1934, Serial No. 52,561

Term of patent 3½ years

To all whom it may concern:

Be it known that I, NICHOLAS J. GROSSMAN, a citizen of the United States, residing at Lynn, in the county of Essex, and State of Massachusetts, have invented a new, original, and ornamental Design for a Shoe, of which the following is a specification, reference being had to the accompanying drawing, forming part thereof.

Fig. 1 is a top plan view of a shoe showing my new design; and

Fig. 2 is a side view of the shoe.

I claim:

The ornamental design for a shoe, as shown.

N. J. GROSSMAN.
